Primary Examiner — Elizabeth Albert(74) *Attorney, Agent, or Firm* — Alix, Yale & Ristas, LLP(57) **CLAIM**

The ornamental design for a pencil sharpener, as shown and described.

DESCRIPTION

FIG. 1 is a perspective of a pencil sharpener showing the new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines in the drawings illustrate unclaimed portions of the pencil sharpener and form no part of the claimed design.
